UNITED STATES PATENT OFFICE.

RAYMOND E. SERVIS AND FREDRICH J. RODE, OF CHICAGO, ILLINOIS, ASSIGNEES TO MARQUETTE TOOL & MFG. COMPANY, OF CHICAGO, ILLINOIS, A CORPORATION OF ILLINOIS.

BLANK-HOLDING MEANS.

Application filed December 6, 1924. Serial No. 754,348.

To all whom it may concern:

Be it known that we, RAYMOND E. SERVIS and FREDRICH J. RODE, citizens of the United States, residing at Chicago, in the county of Cook and State of Illinois, have invented certain new and useful Improvements in Blank-Holding Means, of which the following is a specification.

This invention relates to fluid-pressure 10 cushions for use in drawing in one operation, metal shapes or shells of a greater depth than is ordinarily possible to draw in one operation, and is particularly adapted though not necessarily limited in its use in 15 connection with what is termed a single-action mechanical press.

In presses of this character there is provided a plurality of draw rings or blank holding means which co-operate with the 20 die, the blank being held between the draw ring or blank holding means and the ram during the forming or shaping of the article. These draw rings are usually arranged one 25 with the other, one of the rings being held by fluid pressure, against operation while the other ring is moved during the first portion of the cycle of operation of forming or shaping the blank over the stationary die and over the other die ring.

After the completion of the first portion 30 of the cycle of operation in forming or shaping the article, and during the same stroke of the ram, the article is further shaped over the stationary die, the inner draw ring being 35 then moved against the fluid pressure acting thereupon.

The fluid pressure upon the inner draw ring must of necessity be of such a degree 40 that the ring will not be moved during the first portion of the formation of the article, with the result that during that portion of 45 the cycle of operation of the press in which the inner draw ring is moved, the ram must overcome the excess fluid pressure to complete the formation or shaping of the article. This results in a strain upon the 50 crank shaft and clutches and reduces the capacity or scope of the press.

It is one of the objects of the present invention to overcome these difficulties and objections and to provide improved means to 60 positively lock in a fixed position one of the blank holding members or draw rings while the other member or blank holding means is

allowed to remain movable under the action 55 of the ram, and to provide improved means for unlocking or releasing the locked member to allow it to move at a predetermined point or time in the cycle of operation of the press.

A further object is to provide improved 60 means operating automatically to lock one of the blank holding means against movement and to automatically unlock or release the blank holding means for movement.

To the attainment of these ends and the 65 accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a vertical, longitudinal sectional view of a blank holding means constructed in accordance with the principles of this invention and showing the parts in their initial or starting position in the formation 70 of the article;

Fig. 2 is a view similar to Fig. 1 showing the parts in another position;

Fig. 3 is an enlarged detail view taken on line 3—3, Fig. 1, of the locking mechanism; and

Fig. 4 is a sectional view taken on line 4—4, Fig. 1.

Referring more particularly to the drawings the numeral 10 designates the bolster plate of a press, having mounted thereupon 90 a stationary die member 11, with which a cutting member 12 co-operates.

Co-operating with the die is another die member 13 carried by the ram or a movable part of the press, and this die member 13 95 co-operates with the member 12 to cut or shear the material 14 and is so shaped that it will pass between the dies 11 and 12 to shape the material over the die 11, all in a manner as well known in this art.

Encompassing the die 11 are a plurality of draw rings or blank holding members 15—16, one arranged within the other, and these members 15 and 16 are respectively supported by means of pins 17 and 18 that 105 pass loosely through the bed plate or bolster 10.

Supported below the bolster plate 10 is a

fluid controlled cushioning device, preferably embodying an inverted cylinder 19 which telescopes over another cylinder 20, the latter resting upon a plate or member 21, 5 which forms a closure for the cylinder 20 and this plate or member is supported from the bolster or bed plate 10 in any desired or suitable manner, such as by means of bolts 22, which latter are threaded into the bolster plate 10 and also pass through the plate or member 21. Nuts or collars 23 are carried by these bolts 22 for holding the parts in position.

The end 24 of the cylinder 20 serves as a 15 piston operating in the cylinder 19 and suitable packing 25 may be provided between the piston and the cylinder.

Operating in the cylinder 20 is a piston 26 provided with suitable packing rings 27. 20 A piston rod 28 is connected with the piston 26 and passes through the end 24 of the cylinder 20, suitable packing 29 being provided for the piston rod where it passes through the cylinder head 24. This piston rod also 25 passes through the end 30 of the cylinder 19 and a suitable packing 31 is provided for the piston at the point where it passes through the end of the cylinder 19. The cylinder 20 is provided with an inlet 32 to which is connected a supply pipe 33 that receives a supply of fluid from any suitable source. The cylinder 19 is also provided with an opening 34 connected with which is a suitable pipe 35 adapted to be supplied with fluid from any suitable source, and both of these openings 32 and 34 serve as outlets for the respective cylinders so that the fluid will flow into and out of the cylinders through the same respective openings.

40 The pins 18 which support the outer draw ring or blank holding member 16 engage and rest upon the end 30 of the cylinder 19, and the pins 17 which support the inner draw ring or blank holding member 15 engage and rest upon the end of the piston rod 28. If desired a head or enlargement 36 may be provided on the end of the piston rod and against which the pins 17 engage.

45 The piston rod 28 is provided with an extension 37 depending therebelow and which extension passes through the plate or member 21 therebeyond, and suitable packing 38 is provided for the extension 37 where it passes through the plate or member 21.

Supported preferably by the plate 21 and depending therefrom is a bracket 39, one end 40 of which is arranged below and in alignment with the end of the extension 37 and is preferably bifurcated as at 41. Links 42 and 43 are pivotally connected by one end as at 44. The free end of the link 43 is pivotally connected as at 45 with the end 40 of the bracket 39 and stands within the

bifurcation 41. The free end of the link 42 projects into a bifurcation 46 in the lower extremity of the extension 37 of the piston rod 28 and is pivotally connected with the end of the extension 37 by means of a pivot 70 pin 47. One end of the pin projects laterally beyond the extension 37 as at 48 and the extended portion 48 of the pin moves in a guide formed by means of a slot 49 in an extension 50 of the bracket 39 so as to guide 71 the pin 48 in its vertical movement.

The free end of the link 42 is loosely connected with the end of the extension 37, that is to say there is provided a slot 51 in the end of the link 42 to provide a slight lost motion between these parts and to permit the link 42 to have a proper movement during the operation of the device.

55 The links 42 are provided as a means for locking the inner draw ring or blank holding member 15 against movement during the first portion of the cycle of operation of the machine and while the blank 14 is being formed over the die 11 and the blank holding member 15.

This is accomplished by reason of the fact that when the blank holding member or means 15 is in a position substantially flush with the top of the die 11 the pivots 44-45 and 47 of the links will be arranged in alinement.

In order to permit the movement of the blank holding means 15 during the cycle of operation of the press it, together with the piston rod 28 and extension 37, must be unlocked or released. This is accomplished by moving the pivot 44 of the links 42 and 43 out of alinement with the pivots 45 and 47 so as to knuckle the links with respect to each other. This may be accomplished in any desired or suitable manner but preferably by means of a pin 52 which is slidably mounted upon the bracket 39 so as to move in directions transverse to the length of the links so as to engage the links on one side of the pivot 44 to exert pressure upon the links and cause them to knuckle. This pin 52 may be provided with an adjustable head 53 held in its adjusted position by means of a suitable nut or collar 54. The pin 52 is of a length that the other end 55 thereof will extend beyond the bracket 39 and if desired a shoulder 56 may be provided on the pin which is adapted to co-operate with a shoulder 57 to limit the movement of the pin in one direction.

An operating bar or rod 58 is provided for actuating the pin 52. This bar or rod 58 slides loosely through the plate 21 and the bracket 39 so that the extremity 59 thereof will engage the adjacent extremity of the pin 52. These contacting extremities of the pins 58 and 52 are preferably rounded so as to facilitate and insure operation of the pin 52 by the rod 58. The upper end

of the rod 58 passes loosely through a bracket or extension 60 carried by the cylinder 19 and is threaded as at 61 to receive a nut or collar 62, which latter is adapted to engage and rest upon the bracket or extension 60 to support the rod 58.

An additional nut or collar 63 is provided on the rod 58 and is spaced for a considerable distance from the nut or collar 62 and 10 into and out of engagement with the nut or collar 63 the bracket or extension 60 on the cylinder 19 is adapted to move during the operation of the press.

When the cylinder 19 is lowered the 15 bracket or extension 60 engages the nut or collar 63 and lowers the rod 58 and this movement of the rod 58 will force the pin 52 forwardly to knuckle the links 42 and 43 as shown in Figure 2.

20 This operation takes place just before the die 13 commences to force the blank holding means or member 15 downwardly to form the article over the die 11.

At the completion of the operation of 25 forming the article and as the cylinder 19 ascends the extension 60 will engage the nut or collar 62 and raise the bar or rod 58 so as to release the pin 52. As the piston rod and extension 37 move upwardly with the 30 piston 26, the links 42 and 43 will be straightened from the position shown in Fig. 2 to the position shown in Fig. 1. This straightening movement of the links causes the link 42 to force the pin 52 backwardly and when the links have been straightened 35 so that the pivots 44, 45 and 47 are in alignment, the piston rod 28 will be again locked against operation.

It is thought that the operation of this 40 apparatus will be clearly understood from the foregoing, but briefly stated it is as follows. The cylinder 19 and piston 26 are held in their normal positions by means of fluid pressure admitted into the cylinders 45 19 and 20 from the source of fluid supply, and when in the position shown in Figure 1, the blank holding means or member 15 will be locked against movement.

As the die 13 descends the first operation 50 will be the shearing of the metal 14 by the die 13 and shearing member 12. A continued movement of the die 13 in a downward direction will shape the material over the die 11 and blank holding member 15, the latter being locked against operation. As 55 the blank holding means 16 descends the pins 18 will lower the cylinder 19 against the fluid pressure therein and this operation will continue until the blank holding member 16 reaches the limit of its downward movement. Just at this point in the cycle 60 of operation of the machine the bracket or extension 60 on the cylinder 19 will engage the nut or collar 63 to force the rod 58 downwardly, the latter forcing the pin 52

forwardly. When the end of the pin 52 engages the link 42 it will swing the links 42 and 43 about their pivots 47—45 to move the pivot 44 out of alignment therewith. This will knuckle the links 42 and 43 sufficiently 70 to release the piston rod 28 and the blank holding means 15.

When thus released, a further movement of the die 13 in a downward direction will shape the material 14 over the die 11 and 75 the blank holding means or member 15 will be depressed by the die 13 against the fluid pressure in the cylinder 20, through the medium of the pins 17.

This will complete the operation of the 80 forming of the article.

When the ram or die 13 recedes the cylinder 19 will be elevated by fluid pressure as will also the piston 27. This will return the draw rings or blank holding members 16—15 85 and will straighten the links 42 and 43 with respect to each other so as to move the pivot 44 thereof in alignment with the pivots 45 and 47, thereby again locking the blank holding means or member 15 against opera- 90 tion.

Obviously the nut or collar 63 may be adjusted to vary the time of operation of the pin 52 to unlock the blank holding means 95 or member 15.

While the preferred form of the invention has been herein shown and described it is to be understood that various changes may be made in the details of construction and in the combination and arrangement of the several parts, within the scope of the claims, without departing from the spirit of this invention. 100

What is claimed as new is:—

1. A draw press including a plunger, a plurality of blank holding means adapted to successively co-operate with the plunger to clamp the work, means operable to positively lock one of the blank holding means against operation during the operation of the other blank holding means, the said locking means including a toggle, and means for rendering the locking means inactive to release the blank holding means locked thereby. 105

2. A draw press including a plunger, a plurality of blank holding means adapted to successively co-operate with the plunger to clamp the work, means operable to positively lock one of the blank holding means against operation during the operation of the other blank holding means, the said locking means including a toggle, and means responsive in its operation to the operation of one of the said blank holding means for rendering the said locking means inactive to release the blank holding means locked thereby. 110

3. A draw press including a plunger, a plurality of fluid pressure controlled blank 120

125

130

- holding means adapted to successively co-operate with the plunger to clamp the work, means operable to positively lock one of the blank holding means against operation during the operation of the other blank holding means, the said locking means including a toggle-like device, and means operable to knuckle the said toggle-like device to release the blank holding means locked thereby.
4. A draw press including a plunger, a plurality of fluid pressure controlled blank holding means adapted to successively co-operate with the plunger to clamp the work, means operable to positively lock one of the blank holding means against operation during the operation of the other blank holding means, the said locking means including a toggle-like device, and means controlled in its operation by the actuation of one of the said blank holding means for knuckling the said toggle device to release the blank holding means locked thereby.
5. A draw press including a plunger, a plurality of blank holding means adapted to successively co-operate with the plunger to clamp the work, a toggle-like construction operatively connected with one of the blank holding means for locking the latter against operation during the operation of the other blank holding means, and means responsive to the operation of the blank holding means for knuckling the said toggle-like device to release the blank holding means locked thereby.
6. A draw press including a plunger, a plurality of blank holding means adapted to successively co-operate with the plunger to clamp the work, a toggle-like device operatively connected with one of the blank holding means for locking the latter against operation during the operation of the other blank holding means, a plunger operable to knuckle the said toggle device to release the blank holding means locked thereby, and a shifting device adapted to shift the plunger at a predetermined time in the cycle of operation of the press, the said shifting device being responsive in its operation to the operation of one of the said blank holding means.
7. A draw press including a plunger, a plurality of blank holding means adapted to successively co-operate with the plunger to clamp the work, a toggle-like device operatively connected with one of the blank holding means for locking the latter against operation during the operation of the other blank holding means, a plunger operable to knuckle the said toggle device to release the blank holding means locked thereby, and a shifting device adapted to shift the plunger at a predetermined time in the cycle of operation of the press, the said shifting device being responsive in its operation to the operation of one of the said blank holding means.
8. A draw press including a plunger, a plurality of blank holding means adapted to successively co-operate with the plunger to clamp the work, a toggle-like device operatively connected with one of the blank holding means for locking the latter against operation during the operation of the other blank holding means, a plunger operable to knuckle the said toggle device to release the blank holding means locked thereby, a shifting device adapted to shift the plunger at a predetermined time in the cycle of operation of the press, the said shifting device being responsive in its operation to the operation of one of the blank holding means, and means whereby the time of operation of the said shifting device in the cycle of operation of the press may be varied.
- In testimony whereof we have signed our names to this specification, on this 28th day of November, A. D. 1924.

RAYMOND E. SERVIS.
FREDRICH J. RODE.
